ATTYS.

GRINDING METHODS

This is a division of my copending application, Ser. No. 652,743, filed July 12, 1967, now U.S. Pat. No. 3,522,678 dated Aug. 4, 1970, which in turn was a division of my earlier filed copending application, Ser. No. 452,787, filed May 3, 1965, now abandoned.

The present invention relates in general to grinding methods, and has more particular reference to new and improved methods of forming spherical surfaces by grinding procedures, the invention pertaining especially to the formation of a razor blade having a ground edge at and around the periphery of an opening in the blade.

An important object of the invention is to provide methods of grinding spherical surfaces in work pieces; a further object being to provide a cutting edge at the periphery of an opening in blade element; another object being to provide a razor having a ground cutting edge at and peripherally of a hole in a razor blade element; a still further object being to provide a method of grinding a spherically domed surface in a work piece.

Another important object of the invention is to form a shaving edge at the margin of a hole in a razor blade element by grinding the same spherically on one side of the blade.

Another important object is to grind a spherical surface on a work piece by rotating it in engagement with a grinding wheel transversely shaped in conformity with the desired spherical shape to be formed.

The foregoing and numerous other important objects, advantages and inherent functions of the invention will be more fully understood from the following description, which taken in connection with the accompanying drawings, discloses preferred embodiments of the invention.

Referring to the drawings:

FIG. 1 is a side elevation view of a razor embodying the present invention;

FIG. 2 is a top view of the razor shown in FIG. 1;

FIG. 3 is a sectional view taken substantially along the line 3-3 in FIG. 2;

FIG. 4 is an elevational view of apparatus for grinding a convex spherical surface on razor blade elements embodying the present invention and showing the blade element in transverse section; and

FIG. 5 is a view similar to FIG. 4 but showing grinding apparatus wherein the grinding wheel may be rotated about both axes while the blade remains stationary.

To illustrate the invention the drawing shows a razor 11 comprising a thin, sheet metal blade 13 supported in a preferably molded handle 15 of suitable plastic or other readily moldable material. The blade element is formed with one or more preferably circular holes, openings or perforations 17 therethrough, the margins of said openings being sharpened to form peripheral, inwardly facing, fine cutting edges 19 around the holes 17.

As shown more particularly in the drawing, the razor may comprise a single, spherically curved plate or blade 13 formed with a plurality of spaced holes 17 extending therethrough, said holes being preferably circular and having a diameter of the order of four to five-tenths of an inch. Eminently satisfactory results are realized where the diameter of the openings is precisely 0.437 of an inch, although obviously the openings need not be held precisely to the size mentioned. While the plate 13 may be formed with a single opening, if desired, it is preferable to provide three or more equally spaced openings, preferably arranged circularly about and equally spaced from a central point. As shown, it is convenient to provide a spherically curved blade 13 having a circular marginal edge and provided with four circular openings in equally spaced circular arrangement about the center of the plate.

In order to manufacture the razor blade, a thin disc of suitable razor blade material, such as carbon steel, tool steel, stainless steel and the like, may first be blanked to size. It may then be pressed or otherwise shaped to the desired spherical configuration, the radius of curvature being preferably of the

order of 2 inches. The convex side of the blank may then be ground precisely to form a surface 20 having the desired radius of curvature. The holes 17 may be pierced, punched or otherwise formed in the disc, after which beveled surfaces 21 may be machined at the edges of the openings 17, on the concave side 23 of the plate 13, and also at its peripheral edge. The blade may then be tempered to obtain desired hardness.

Finally, the handle 15, which may be made of high-impact styrene, nylon or like material, may be applied to the peripheral edges of the blade 13, as by injection molding, said handle, preferably comprising a cylindrical portion 22, having a seat 24 securely receiving the beveled peripheral edge of the plate 13, at one end of said cylindrical portion. The handle also preferably has an outwardly extending flange 25 spaced away from the seat 24. The periphery of the flange 25 may be roughened by diamond knurling the same, as shown at 27, to provide firm finger grippage for the manipulation of the razor.

It will be seen from the foregoing that the present invention pertains to a new type of razor which may be used for shaving hair from the surface S of any part of the body, and particularly to a novel method of grinding to form the cutting edges thereof. The razor of the present invention is of unique construction in that it does not require any special type of holder or guard for the blade. The razor is unusual, also, in embodying a spherical blade element having one or more holes marginally ground to a fine, sharp cutting edge is pressed upon and wiped across the surface to be shaved, the skin protrudes itself slightly into the hole, thereby exposing the hairs of shaving. By applying a circular motion of the razor, a shearing action is produced upon the hairs, because of the mutually inwardly facing character of the shaving edge. Accordingly, a smooth, clean shave may be obtained with a minimum of shaving strokes.

By providing a plurality of relatively small razor edged holes, the possibility of cutting the skin while shaving is minimized, and, indeed, substantially prohibited. The reason why inadvertent cutting of the skin, while shaving, is substantially inhibited, is, first, because the area of skin exposed in the blade opening is relatively small, and, second, because there is no opening disposed centrally in the razor; but the hole or holes are all offset radially from the center of the razor, the several shaving openings being all grouped circularly around the center of the razor. As a consequence, when the razor is held by the rim 27, the cutting action is always of shearing character while the razor gyrates circularly across the surface of the skin being shaved. If a centered hole were to be provided in the razor, it would be possible to rotate the razor about the center of the shaving opening, in which case there would be a tendency to cut a circle of skin without cutting any hair. It is therefore desirable that no shaving opening be centered in the razor.

The number of shaving openings and their relative size may be varied, of course; but it has been experimentally determined that four holes, having a diameter of the order of 4 to five-tenths of an inch, that is to say seven-sixteenths±one-sixteenth of an inch, at the honed cutting edges thereof, and disposed about the center of the razor, in the manner shown in FIG. 2 of the drawings, appears to be a practical and satisfactory, if not optimum, arrangement.

The unitary spherically curved blade of the razor shown in FIGS. 1-5 is unique in that the cutting edges of the blade are formed by the intersection of two spherical surfaces, so that a sharp cutting edge may be easily ground and lapped or honed, since it is unnecessary to maintain any close tolerance relationship between the outside radius of the blade, which is preferably of the order of 2 inches, and the spherical radius of the inner inclined sides 21 of the cutting edges, at the several openings, which is of the order of one-half inch. These inner inclined sides of the cutting edges are preferably ground and lapped by a ball having a diameter of the order of 1 inch, as shown more particularly in my above referred to U.S. Pat. No. 3,522,678.

This form of blade has an inherent design limitation in that the angle of incidence of the cutting edges 19 upon the surface S being shaved, which cannot be varied, is determined by the curvature of the outer spherical surface of the blade element 13. It has been determined that, under certain circumstances, it is desirable to have a somewhat steeper angle of incidence of the cutting edge with respect to the surface being shave, that is to say, an angle that provides more scraping action. This, of course, could be accomplished by bulging the edges of each hole outwardly, thereby making the grinding of the cutting edge extremely difficult because of the necessity of working upon the outer surfaces of conically bulged edge portions of the holes.

As shown more especially in FIGS. 4 and 5 of the drawing, the convex surface of the blade 13, may be formed by grinding the same with a generally concave spool-shaped wheel 31, preferably mounted for rotary grinding movement about its axis 32. The side surfaces of the wheel are dressed to the sectional shape of the spherical curvature desired in the blade. The blade 13 to be lapped may be mounted on a support base 33 having a spherical blade carrying portion 35, upon which the blade may be secured in any preferred fashion, as by means of cement. The support 33 has an axis 37 extending centrally of the spherical portion and through the center of curvature thereof, and the blade element to be lapped is secured on the support with its center coincident with the axis 37. The grinding wheel and support base with blade element secured thereon may then be brought into grinding relationship presenting the blade element against the shaped side of the wheel, with the axis 37 of the support extending normal to the axis 32 of the wheel and in the medial plane of its dressed surface, that is to say, its plane of minimal diameter.

For optimum grinding performance, the wheel 31 and blade carrying support 33 should be relatively rotated about the axis 37. This may be done by rotating the support and mounted

blade about the axis 37 while spinning the grinding wheel about its rotary axis 32. Alternately, the support 33 and mounted blade may remain stationary and the spinning wheel 31 may be mounted in a trunnion 38 for rotation about the axis 37 while spinning about the axis 32. In either case the dressed wheel will grind the desired spherical curvature into the convex surface of the blade mounted on the support 33.

It is thought that the invention and its numerous attendant advantages will be fully understood from the foregoing description, and it is obvious that numerous changes may be made in the form, construction and arrangement of the several parts without departing from the spirit of scope of the invention, or sacrificing any of its attendant advantages, the forms herein disclosed being preferred embodiments for the purpose of demonstrating the invention.

I claim:

1. The method of grinding the convex outer surface of a thin razor blade having a spherically convex outer surface and a spherically concave inner surface and having a plurality of edge sharpened openings therethrough, which comprises mounting the blade on a support, placing in contact with the convex surface thereof a generally concave spool-shaped grinding wheel having a spinning axis and an arcuate grinding surface formed to the sectional shape of the spherical curvature of said convex surface, and simultaneously spinning the grinding wheel about its spinning axis and relatively rotating the grinding wheel and blade about an axis which is normal to said spinning axis and which extends through the center of the blade, while in contact with said convex surface of the blade.

2. The method of grinding defined in claim 1 wherein the step of relatively rotating the grinding wheel and blade is accomplished by rotating the grinding wheel and maintaining the blade stationary.

UNITED STATES PATENT OFFICE
CERTIFICATE OF CORRECTION

Patent No. 3,631,641 Dated January 4, 1972

Inventor(s) Harold W. Scholten

It is certified that error appears in the above-identified patent
and that said Letters Patent are hereby corrected as shown below:

Column 1, line 5, "may" should read -- my --; line 50,
"element is" should read -- element 13 is --; line 48, "thin,
sheet" should read -- thin sheet --.

Column 2, line 26, "edge is" should read -- edge around the
borders of the hole or holes. When the spherical blade --;
line 28, "of" should read -- for --.

Signed and sealed this 18th day of July 1972.
